UNITED STATES PATENT OFFICE.

JAMES HERMAN ABBOTT, OF PHILADELPHIA, PENNSYLVANIA.

METHOD OF MOUNTING FOR AND BY TUBULAR DEVICES.

1,105,590.

Specification of Letters Patent.

Patented July 28, 1914.

Original application filed June 16, 1911, Serial No. 633,518. Divided and this application filed October 12, 1912. Serial No. 725,368.

To all whom it may concern:

Be it known that I, JAMES HERMAN ABBOTT, a citizen of the United States, residing at 2534 South Twentieth street, Philadelphia, in the county of Philadelphia and State of Pennsylvania, have invented a certain new and useful Method of Mounting for and by Tubular Devices, of which the following is a specification.

10 The purpose of my invention is to afford effective and simple concealed means for retaining tubular parts upon a support or spindle at any point thereon.

A further purpose of my invention is to stretch a tubular member sidewise by lugs or extensions upon the support, to draw the intermediate tube portions into a groove, recess or depression in the support and to restore the initial shape of the tube in the 20 rear of the stretched part.

A further purpose of my invention is to retain a tubular member or part connected therewith or supported thereon against longitudinal movement upon a support, for 25 convenience here termed a spindle, by distortion of a tubular member through longitudinal movement thereof.

A further purpose of my invention is to form retaining, coöperating grooves, or flattened portions upon a tubular member, so surrounded by other structure that it is not accessible from a lateral direction.

I have illustrated my invention by that form thereof which has in practice proved 35 simplest, cheapest and most effective.

Figure 1 is a longitudinal section of a structure embodying my invention. Fig. 2 is a longitudinal section of the structure of Fig. 1 taken at right angles thereto. Fig. 40 3 is a transverse section of Fig. 1 omitting the bristles thereof. Fig. 4 is a longitudinal section of the parts shown in Fig. 3 prior to their assemblage. Fig. 5 is a perspective of the form of support, here a 45 spindle, preferred by me. Fig. 6 is a longitudinal section of a spindle supporting parts of different shape from those in Figs. 1 and 2. Fig. 7 is a longitudinal section of a mount in which the part mounted is retained by two embodiments of my invention. Fig. 8 is a side elevation of a support of different cross section and adapted for a mount between its ends. Fig. 9 is a perspective view corresponding to Fig. 5 but with 55 a tube in place. Fig. 10 is a longitudinal section of a structure corresponding to Fig.

1 but making use of a head on the spindle with a shorter tube. Fig. 11 is a longitudinal section showing one construction embodying the parts in Fig. 10.

This application is a division of my co-pending application for mount for tubular devices, Serial No. 633,518, filed June 16, 1911.

While I have illustrated my invention as applied to the mounting of rotatable parts upon spindles of circular section for dental brush uses, it will be evident that its use is not confined to rotatable parts and that it will be suitable for mounting disks, 65 felt buffers and other parts, most of them rotatable, of wide variety in this art, as well as a great variety of structures, whether rotatable or not, in other arts, such for example, as hoes and other garden utensils 70 mounted by means of a ferrule or other tubular part, wherever the parts can be held about or upon a support, pin, spindle or shaft by means of a tubular member laterally distorted locally by a part of the support. 75

Similar numerals of reference indicate like parts in the drawings.

1 designates a support, rotatable in the form shown in Figs. 1, 2 and 6, at whose 85 end a dental brush is mounted. The brush forms a good illustration of my invention, because the structure surrounding the sleeve prevents access from the side to secure the parts by pinching, for example, while permitting the longitudinal movement of a sleeve during one of the movements necessary in constructing the brush.

The brush, in the forms illustrated, comprises retaining disks 2 or 2' and 3 or 3' 95 which are pressed against bristles 4. The bristles may be threaded about a ring 5 and the disks are retained in gripping position by the outwardly turned or flared ends 6, 7 of a tubular member which my 100 invention secures to the shaft 1. The tubular member could itself carry or support any parts to be retained in other relations and not necessarily detached therefrom.

In the form of my invention shown, I 105 compress the spindle, pin or support transversely all the way across, preferably on both sides, to form flattened portions or grooves, as at 8, thus forcing the metal outwardly laterally at the ends of the grooves 110 in the form of lugs, ears, humps, swellings or projections 9 so that the width in the

direction of the flattened portion or groove at this point shall exceed the normal width of the support in this direction or the diameter of the spindle.

5 I prefer to maintain a contour of perimeter as nearly equal as possible to the circumference of the spindle or support in order that the tubular member may not be permanently stretched in girth and, when 10 reshaped by the succeeding portion of the spindle may fit it snugly. In the illustration given I force the spindle or support 1, longitudinally into a tubular member 10 having a contour initially substantially the 15 same as that of the spindle or support, in either direction and either end forward, causing local stretching of the tube laterally at the point of the flattening of the support. The stretching is caused by the lugs or projections and results in the adjoining material of the tube being drawn within the 20 grooves.

Continued movement of the spindle or support into or through the tube results in 25 the material of the tube being progressively bulged at the point corresponding to the lugs or ears and drawn into the groove between at the same time that the portion thus previously drawn into the groove is progressively pressed outwardly to its original 30 diameter by the succeeding cylindrical part of the spindle or support. The outward pressing of the tube along the sides, restoring the width, in Fig. 1 the diameter, of the 35 tube in this direction, results in a corresponding drawing in of the tube along the sides where it has been bulged previously by the lugs or ears 9, substantially restoring the initial contour, whatever the previous 40 shape.

The extent of initial distortion of the tube and the approximation to restoration will depend upon the size of the lugs or ears and groove or flat portion, *i. e.*, the deviation 45 from the initial shape, upon the tightness of fit of the tubular member and the thickness, elasticity and malleability of the tube itself, and should be selected and proportioned to 50 secure as little distortion and as complete restoration to shape as the requirements of the use intended permit. The distortion desirable for dental brush purposes has been exaggerated for purpose of clearness of 55 illustration of this use. Brush mounts have been found not to require nearly the change of contour represented.

The length of spindle or support represented by the lugs or ears from the point 11 to the point 12 is also to be selected and 60 proportioned with reference to the length of the tubular member mounted thereon so that the restoration of the tube to shape may be complete, if possible, and the hold as well as the neatness of appearance, may be thus 65 enhanced.

It will be evident to all familiar with metal working that, in the example chosen, Figs. 1, 2 and 6, the straight end 13 of the tube shown in Fig. 4 may be outwardly turned to any desired extent after the disks 70 2 or 2' and 3 or 3' have been pressed together upon the bristles. A head, such as is shown in Fig. 10, or other stop may be made to take the place of the flange carried by one end of the tube. The stop may be 75 located at any desired point along the spindle length. While I prefer, in these examples, to press the disks together, turn the end of the tube and force the spindle or pin into place by a single movement of a pair 80 of dies, it will be evident that the outward turning of the end 13, where this is done, to form the flange 6 may be done before or after the placing of the spindle within the tube. This makes it possible to seat the 85 tubular member 10 upon the part of the spindle whose contour has been altered before, after or during the assemblage of the brush parts.

In Figs. 1 to 7 I contemplate the mounting of a tubular member upon the end of a spindle because the parts shown are ordinarily there mounted. In Fig. 8, however, I show the grooves 8' and lugs or ears 9' near the longitudinal center and the mount as 95 square in section in order to here point out that my invention is independent of the longitudinal position upon the support and of the initial cross-sectional shape of the support and that this support need not be 100 adapted for rotation.

In Fig. 6 I show a brush of different shape from that of the brushes in Figs. 1-4, mounted in the same manner as they are 105 mounted.

In Fig. 7, I illustrate how two applications of my invention may be used to secure a relatively thick part to a shaft without a continuous tube, preferring to use two tubes in this form to using one long tube with a single variation in section at any desired point in its length. The tubes are here pressed inwardly and are rigidly retained wherever they stop, as in every form, but use but one end of the tube for retaining 110 purposes.

In Fig. 9 I have shown a perspective corresponding generally to Fig. 5, showing a tubular member or sleeve upon a spindle of the type shown in Fig. 5 to illustrate the 115 conformation of the tube to the shape of the spindle. The end of the tube is shown as projecting, but not flared.

In Fig. 10 I have illustrated the use of an 120 enlargement, which, because of the position selected for the illustration, is shown as a head 14 rather than a collar or ring, upon the spindle. It is used in place of the flare of the end of the tube for co-operation with the tube to retain any structure upon a 125 130

spindle or support. This is used here for retention of one of the disks of a dental brush. The tubular member in this illustration is provided with a flange 6 but its end

5 13 is not intended to be flared. The tubular part is forced over the lugs 9 and the disks of the brush are intended to be held between the enlargement upon the spindle and the flared end 6 with the outer parts of the disk

10 faces in compression against the bristles of the brush.

The use of the single tubular member here shown is the same in character as that made of each of the tubular members shown in

15 Fig. 7 and this use would be the same independent of the position along the length of the support or spindle occupied by the co-operating collar, enlargement or ring 14. It will thus be seen that the longitudinal 20 movement involved in my process does not interfere with any surrounding structure and that the distortion of the tube remains at the point of distortion of the mount only.

As best seen in Figs. 10 and 11, the distortion upon the mount may be used to stop movement in one direction only. In these forms the head upon the spindle is used to prevent movement tending to pass the sleeve over that end of the spindle and the distortion 30 of the spindle is effective against movement away from the head chiefly, if not entirely, since the short sleeve has there

been shoved so far toward the head as to leave practically no sleeve unaffected by the projections 9. All of it is there still distorted, or has been distorted and re-formed.

It will be evident that the article, or device which is to be mounted by my method, may be integral with the tubular member, or sustain any desired relation thereto at the 40 wish of the designer.

Having thus described my invention, what I claim as new and desire to secure by Letters Patent is:—

1. The process of securing a tubular fastener upon a support which consists in forcing the fastener longitudinally upon a support of generally uniform sectional shape altered at one point until a part of the tubular member has passed over the altered 50 section and has been reshaped by the succeeding section.

2. The process of securing a tubular member upon a support which consists in forming the support of differing cross sectional shapes having substantially the same perimeter in contiguous sections and forcing the tubular member so as to lie partly upon each of the differing sections of the support.

JAMES HERMAN ABBOTT.
